COMPRESSOR FOR REFRIGERATING APPARATUS

Earl F. Hubacker, Highland Park, Mich., assignor to Borg-Warner Corporation, Chicago, Ill., a corporation of Illinois

Application February 5, 1940, Serial No. 317,223

2 Claims. (Cl. 230—207)

This invention relates to the art of refrigeration and has particular reference to a new and improved form of refrigerating system and motor compressor unit for use therein.

A principal object of the invention is to provide an improved refrigeration system of the compressor-condenser-expander type, wherein a motor compressor unit is arranged in a sealed casing which forms a part of the low pressure side of the system.

Another object of the invention is to provide a new and improved form of motor compressor unit for use in refrigerating systems.

Another object of the invention is to provide a novel form of motor compressor construction which is better adapted for use in a sealed unit.

Another object of the invention is to provide a novel form of rotary compressor construction which is arranged in a bath of oil subjected to the suction pressure of the compressor, with provisions for supplying oil under the discharge pressure of the compressor to certain of the moving parts thereof for sealing and lubrication purposes.

Other objects and advantages of the invention will be apparent from a consideration of the following specification taken in conjunction with the accompanying drawings, of which there are two sheets and wherein:

Fig. 1 is an elevational view of a refrigerator having a refrigerating system which embodies my invention;

Fig. 2 is a vertical sectional view, with parts broken away, of the motor compressor part of the system;

Fig. 3 is a sectional view through the compressor of the motor compressor unit, taken in a plane along the line 3—3 of Fig. 2, looking in the direction of the arrows;

Fig. 4 is a horizontal section of the compressor, taken in a plane along the line 4—4 of Fig. 2, looking in the direction of the arrows; and

Fig. 5 is a bottom plan view of the compressor, taken generally in a plane along the line 5—5 of Fig. 2.

Referring now to Fig. 1, there is illustrated a part of a refrigerator which includes a heat insulated provision compartment 10 having a heat absorbing element 12 of a refrigerating system arranged therein. Said system further includes a motor compressor unit 14 and a condenser 16 operatively connected with the heat absorbing element or evaporator 12. Gaseous refrigerant is returned from the evaporator 12 to the motor compressor unit 14 by the suction line 18, and 55

from the motor compressor unit, high pressure refrigerant vapor is conducted by a conduit 20 to one end of the condenser. From the other end of the condenser, liquid refrigerant is supplied by liquid line 22 to the evaporator under the control of a suitable regulating means. In the system herein illustrated, the casing of the motor compressor unit 14 forms a part of the low pressure side of the system, as will be further explained herein.

The construction of the motor compressor unit is more particularly illustrated in Figs. 2, 3, 4 and 5 and in general comprises a sealed casing 24 having arranged therein an electric motor 26 and a rotary compressor 28. The casing 24 may, as illustrated, comprise a deep-drawn shell 25 closed by a cap 27, the edges of the cap 27 and the shell 25 being flanged outwardly and hermetically connected such as by welding. The interior of the casing 24 comprises a low pressure refrigerant gas and lubricant reservoir, the lubricant collecting in the bottom of the reservoir to approximately the level of the joint between the shell 25 and casing 27.

25 A frame, comprising a sleeve 30 and a bearing plate 32, is supported within the casing 24 and above the bottom thereof, the sleeve preferably being pressed into the shell 25 of the casing 24, as illustrated. The periphery of the bearing plate 32 and the lower end of the sleeve 30 preferably are provided with complementary interfitting aligning surfaces, so that the axis of the bearing 34 coincides with the axis of the sleeve 30 and the bearing plate 32 may be removably assembled to the sleeve 30 by means of a plurality of bolts 36, the threaded portions of which are received in nuts 38 carried by the sleeve 30. Bearing plate 32 is circular and includes an axially extending projection which forms a bearing 34 for a shaft 37. The bearing plate 32 is provided with several apertures 40 so as to permit lubricant to drain into the lower part of the casing 24. The motor 26 includes a stator 42, which is press-fitted in the sleeve 30, and a rotor 44 which is arranged inside of the stator and affixed to the upper end of shaft 37 for driving the same. Current is supplied to the stator 42, for energizing the same, by means of several insulated conductors 46, which make a sealed joint between the current conducting wire and the casing 24.

The bearing plate 32 is provided with a projection on the under side thereof, which forms an end plate 48 of a rotary compressor and which further includes a cylinder 50, a rotor 52, a divider 54, an eccentric 56, a bottom end plate

58, and a valve plate 60. The end plates 48 and 58 and the cylinder 50 are rigidly assembled together in such a way as to form a closed cylindrical chamber or pumping space and in which the rotor 52 is arranged for oscillation. The rotor 52 is freely journaled on the eccentric 56 and, it will be observed, is of less diameter than the pumping chamber 62 in which it is arranged. The rotor 52 is of such size, relative to the cylinder 50, that there is a small working clearance between the horizontal faces of the rotor and the adjacent horizontal faces of the end plates 48 and 58. Also, the diameter of the rotor 52 is such that there is a slight clearance between the periphery of the rotor 52 and the adjacent cylindrical wall of the pumping chamber 62 at that point where the rotor 52 divides one side of the pumping chamber 62 from the other side thereof, as illustrated in Fig. 3, and this clearance is maintained as the rotor gyrates or moves around the pumping chamber 62 in a counter-clockwise direction, looking at Fig. 3.

The divider 54 is arranged for reciprocation within a slot formed in the cylinder 50 and is biased into engagement with the periphery of the rotor, as illustrated in Fig. 3, so as to separate the suction gas from the discharge gas in the pumping chamber 62. The divider 54, it will be observed, comprises a major segment of a cylinder and includes a flat surface which slides on a flat surface of the slot in which the divider 54 reciprocates. The divider 54 preferably is of the same vertical dimension as the rotor 52, so that the divider 54 will form a moving seal between the periphery of the rotor 52, and the walls of the pumping chamber 62. The slot in which the divider or blade 54 operates is of such size that the pressure on the discharge side of the chamber 62 is communicated to the space at the back of the slot behind the divider, so that the difference in pressure between the intake and discharge sides of the compressor will function to aid in causing the divider 54 to follow the rotor 52 upon oscillation thereof.

The pumping chamber is provided with an intake port at 64 and with a valve controlled discharge port at 66. The divider 54 is guided in its movement by a pin 68 which is slideable in a bore formed in the wall of the cylinder, one end of the pin being seated in a cavity in the rear side of the divider or blade 54 and the other end of the pin, which extends outside of the cylinder 50, being provided with a cap 70 upon which is seated one end of a spring 72, the other end of the spring being seated in the end of a cap 74 which is screw threaded on to a projection 76 formed on the external wall of the cylinder 50. Spring 72, through pin 68, acts to hold the divider 54 in contact with the periphery of the rotor 52. The intake port 64 is connected by a tube 78 to the upper part of the casing 24, the upper end of the tube 78 being open. The discharge port 66, which is formed in the end plate 58, opens into a chamber 80 in which the valve 82, which controls the discharge port, is arranged. The valve 82 is a flap or check valve and is anchored at one end thereof by means of screws 84 to the under side of end plate 58. The discharge tube or conduit 20 has one end thereof seated in an opening 86 in the valve plate 60 which communicates with the chamber 80, and such discharge tube 20 extends through a sealed opening in the casing 24 and serves to conduct the compressed gas dis-

charged by the compressor to one end of the condenser.

One end of a duct 88 formed in the end plate 58 and valve plate 60 communicates with the bottom of the chamber 80, and the other end of such duct 88 communicates with a groove 90 formed in the shape of an arc and in the upper surface of the end plate 58 and directly opposite the rotor 52. Another duct 92, formed in the valve plate 60, end plate 58 and cylinder 50 (Fig. 3) at one end thereof, communicates with the lower part of chamber 80 and at the other end thereof communicates with the space enclosed by the cap 74. The space within the cap 74 is sealed from the space exteriorly thereof by the threaded connection between the side of the cap 74 and the projection 76 formed on the external wall of the cylinder 50. The chamber 80 serves as an oil trap, and from the bottom of the chamber 80 oil under the discharge pressure of the compressor is forced through ducts 88 and 92 to the groove 90 and to the space enclosed by the cap 74. The oil supplied to the groove 90 under the discharge pressure of the compressor serves to seal the clearance between the end of the rotor 52 and the end plate 58, while the oil supplied by the duct 92 to the space within the cap 74 is forced past the pin 68 and into the back of the slot in which the divider reciprocates, for lubrication and sealing purposes, particularly for the purpose of supplying lubricant to the clearance between the ends of the divider 54 and the cylinder end plates 48 and 58 and to the flat surface upon which the divider 54 slides.

The bottom end of the eccentric 56 slides upon the upper surface of the end plate 58 which thereby forms a thrust bearing for the shaft 37. The end plate 58 may be provided with a groove 94 at the center thereof and as illustrated in Fig. 4. This groove 94 is supplied with oil, as will be explained hereinafter. The end plate 58 and valve plate 60 are provided with openings coincident with the axis of the shaft 37 and through which openings extends a small diameter screw 100 forming an extension of the shaft 37. The screw 100, on the end thereof which extends below the valve plate 60, is provided with an impeller 102 which rotates within a chamber formed by a stamping 104 secured to the under side of the valve plate 60. The stamping 104 has a central opening 106 through which lubricant from the bottom of the casing 24 is drawn by rotation of the impeller 102, which forces lubricant through a conduit 108 (formed in the valve plate 60, end plate 58, cylinder 50 and end plate 48) into a reservoir 110 formed by an annular ring 112 affixed to the upper side of the bearing plate 32 and around the bearing 34.

From the reservoir 110 oil is supplied by means of a plurality of ducts such as 114 to a chamber 116 formed between the rotor 52 and the end plate 48 and around the lower end of the shaft 37. From the chamber 116 oil is fed upwardly to the surfaces of the bearing by a spiral groove 118 formed in the shaft 37, which serves to pump lubricant upwardly along the shaft 37 and between the same and the bearing 34. The eccentric 56 also is provided with a spiral groove 120 which serves to conduct lubricant from the chamber 116 downwardly through the center of the rotor 52 and to the groove 94 formed in the lower end plate 58. Rotation of the impeller 102 also aids in drawing lubricant from the chamber 116 downwardly through the hollow center of the

rotor 52 and thence downwardly into the chamber in which the impeller 102 is located.

Thus, it will be seen that lubricant is supplied to the shaft 37 and to the eccentric 58 for lubricating the same. Also, the lubricant which is supplied to the chamber 116 and to the groove 94 functions to seal the clearance between the rotor 52 and the end plates 48 and 58. During the operation of the compressor, some lubricant will be drawn through the clearance between the sides of the rotor 52 and the end plates into the chamber 62 on the intake side thereof. Such lubricant, together with the lubricant entrained in the suction gas supplied by the conduit 18 and the lubricant which is forced by the high pressure past the divider 54, will be swept around the chamber 62 by gyration of the rotor 52 and serve to seal the clearance between the rotor 52 and the internal wall of the cylinder 50 as well as to seal the clearance between the ends of the divider 54 and the adjacent end plates. Most of the lubricant which enters the pumping chamber 62 will be discharged along with the compressed gas during the operation of the compressor, but sufficient will remain for the purposes of lubricating and sealing the moving parts of the compressor. The groove 90, as previously explained, is supplied with lubricant under the discharge pressure of the compressor.

The discharge valve 82 will open when the high point, or that part of the rotor 52 closest to the internal wall of the cylinder 50, reaches a point approximately corresponding with the left hand end of groove 90, looking at Fig. 4, and the discharge valve will remain open until the rotor has completed its stroke, which occurs when the high point on the rotor has reached the divider 54. As the pressure in the pumping chamber reaches its maximum, just before and during the time that the discharge valve is open, the pressure drop across the rotor 52, viz., between that part of the pumping chamber 62 in communication with the discharge port and the hollow interior of the rotor, will be the greatest. However, the groove 90 extends across the end plate between such high pressure discharge space and the interior of the rotor and serves to seal more effectively the clearance between the rotor 52 and the bottom end plate 58.

The oil which is forced upwardly along the shaft 37 by the groove 118 escapes at the upper end of the bearing 34 and flows downwardly on to the oil slinger 122 which discharges the oil against the baffle 124, said baffle serving to deflect the oil downwardly and out of contact with the lower end of the stator 42. The oil collects either in the reservoir 110 or by overflow returns through the openings 40 into the reservoir in the bottom of the casing 24. The pump 102 supplies oil to the reservoir 110 at a rate which is faster than that at which the oil will be drawn therefrom through the ducts 114, and the excess oil will overflow and return to the reservoir in the bottom of the casing 24. Due to the circulation of oil over the compressor, the dissipation of heat from the same will be expedited.

It is contemplated that sulphur dioxide may be used as a refrigerant in the system, but due to the fact that the interior of the casing 24 is at a low pressure, the refrigerant in the casing 24 will be in a gaseous form except for the very slight amount which might be absorbed in the oil. However, during the operation of the compressor, the heat of the same, together with the low pressure prevailing within the casing 24, will

serve to keep the lubricant reasonably free of refrigerant. In this manner the lubricant which is supplied to the working parts of the compressor will be substantially free of refrigerant.

Refrigerant gas is supplied to the interior of the casing by suction line 18 which communicates with the vapor space in the evaporator 12. The discharge conduit 20, as previously explained, conducts high pressure gas from the compressor to one end of the condenser 16. In the condenser, which may be an air-cooled finned tube, the refrigerant vapor, due to the dissipation of heat, will be converted into a liquid.

From the first pass of the condenser, liquid refrigerant may be conducted by conduit 21 to an annular jacket 126 formed between the sleeve 30 and a bulged-out portion of the casing 24. Passing through the jacket, the liquid refrigerant under high pressure would absorb heat from the motor windings 26. From the jacket 126 refrigerant is conducted by conduit 23 to the second pass of the condenser, and from the bottom of the second pass of the condenser, liquid refrigerant is conducted by a conduit 17 to a high side float 19 which meters the flow of liquid refrigerant from the high side of the system to the evaporator which is on the low side of the system. The liquid line 22, which conducts refrigerant from the high side float 19 to the evaporator 22, may be a capillary tube, so as to prevent the vaporization of the refrigerant before reaching the evaporator, and this capillary may be soldered to the suction line 18 so as to provide heat exchange between the suction gas in the tube 18 and the liquid refrigerant in the tube 22.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In a refrigerating system having a high pressure side and a low pressure side, a casing comprising a part of the low pressure side and forming a low pressure gas and lubricant reservoir, a rotary compressor in said casing submerged in the lubricant, said compressor including means defining a housing formed with a cylinder therein, a driving shaft having an eccentric within the cylinder, a hollow rotor freely journaled on said eccentric, said cylinder having a slot in the wall thereof, a divider reciprocable in said slot and engageable with said rotor, said cylinder having an intake port on one side of said divider and means defining a pressure responsive discharge valve assembly on the other side of said divider, means defining a lubricant trap in the wall of said housing in direct communication with said discharge valve assembly, and passage defining means for delivering lubricant from the lower portion of said trap under the discharge pressure of said compressor into lubricating contact with the rear of said divider.

2. In a refrigerating system having a high pressure side and a low pressure side, a casing comprising a part of the low pressure side and forming a low pressure gas and lubricant reservoir, a rotary compressor in said casing and including means defining a housing formed therein with a cylinder, a driving shaft having an eccentric within the cylinder, a hollow rotor freely journaled on said eccentric, means for supply-

ing lubricant from said reservoir to the interior of said hollow rotor at both ends thereof, said cylinder having a slot in the wall thereof, a divider reciprocable in said slot and engageable with the periphery of said rotor, said cylinder having an intake port on one side of said divider and means defining a pressure responsive discharge valve on the other side of said divider, means defining a conduit connected to said discharge valve and leading through the wall of said

casing to the high pressure side of said system, said last named means including an oil trap formed in the wall of said housing directly adjacent said discharge valve, and lubricant conveying means including a radial groove formed in the cylinder end wall at one end of the rotor for supplying lubricant from said trap to said rotor under the discharge pressure of said compressor during the operation thereof.

EARL F. HUBACKER.
